ABSTRACT OF THE DISCLOSURE

A paper or cardboard band, that is intended to be hooked around one end of a necktie while the necktie is hung on a display rack and that is adapted to bear the trademark applied to the tie, and/or the maker's name, has a tab portion formed with a tongue that fits into the conventional cloth label sewn on the back of the necktie, to prevent movement of the band on the tie.

The present invention relates to fold-over or hook-on bands for neckties.

When neckties are displayed in stores for retail sale, it is common practice to place around the necktie a band on which is printed the name of the maker of the necktie, the trademark by which the necktie is known, and usually the price of the necktie. These bands are made of cardboard; and each band may have a hook at one end and a slot or notch in the other end to receive the hook to fasten the band around the necktie.

It has been found, in use, that when the neckties are handled by customers looking at the ties on a display rack in order to determine a selection, the band may slip down on the necktie, or may be moved by a customer so that the neckties on the rack present an uneven, unsightly arrangement of bands.

A primary object of the present invention is to provide a fold-over or hook-on band which can be fastened on a necktie in such manner as in ordinary use to prevent it from slipping down on the necktie about which it is wrapped.

Other objects of the invention will be apparent herein-after from the specification and from the recital of the appended claims, particularly when read in conjunction with the accompanying drawing.

In the drawing:

FIG. 1 is a front elevation of a hook-on band made according to one embodiment of the invention, the band being shown unfolded;

FIG. 2 is a fragmentary rear elevational view showing this band hooked around the large end of a necktie and engaged with the conventional cloth label of the necktie; and

FIG. 3 is a fragmentary front elevation looking at the front of the large end of a necktie and showing the band in place.

Referring now to the drawing by numerals of reference, 10 denotes a conventional four-in-hand necktie comprising a strip of fabric folded over along lines 11 and 12 60 to have back panels 14 and 15 which overlap a front panel 16. Ordinarily one of the rear panels overlaps the other, and the two rear panels are stitched together.

Ordinarily, also, a cloth label 20 is disposed crosswise of the rear panels 14 and 15 and sewed as its opposite ends, as by means of lines of stitches 21, 22 to the two panels 14 and 15. Usually the ends of the label 20 are tucked in under the main portion of the label; and it

2

is these tucked-in portions, as shown in FIG. 2, which are sewed to the rear panels 14 and 15 of the necktie, so that the remainder of the label forms a loop free of the tie.

The cloth label may bear the trademark and/or name of the tie manufacturer, and/or the name of the material from which the tie is made.

The hook-on or fold-over band itself is denoted at 25. It comprises a front panel 26, and two side panels or tabs 27 and 28.

10 The side panel or tab 27 is slotted at its free end as denoted at 29 to form a hook 30. The tab or side panel 28 is slit along an arc, as denoted at 32, to receive the hook portion 30 of the tab 27.

15 Tab 28 is formed at its bottom with an integral tongue 34 which extends downwardly, and which is adapted to be engaged in the loop formed by the label 20.

20 The front panel 26 and the tabs 27 and 28 may be scored, as denoted by the dash lines 35, 36, 37 and 38 in FIG. 1 so that when the band is folded around the necktie space will be provided to receive the necktie without bulging or buckling the band or the necktie.

25 The front panel 26 of the hook-on band may be printed with the trademark designating the tie, and/or the manufacturer's name, and/or the price at which the tie is to be sold. The cloth label 20 is permanently attached to the tie, and is sewed to the back of the tie so that it will be out of sight when the necktie is being worn. The hook-on band is used when the tie is hung on a display rack in a store, so that the prospective purchaser may see at a glance what type of tie he or she is buying.

30 In use, the band is folded about the large end of the necktie, and the two tabs 27 and 28 of the band may be hooked together, and the band then slipped down on the necktie to insert the tongue 34 under the label 20, or 35 the band may be folded around the necktie, and the tongue 34 inserted in place behind the band, and then the two ends of the band may be hooked together.

35 While the band has been shown as having a hook formed at one end to engage a slot in the other end, it is obvious that both tabs may be slotted, so as to form both with hooks at their extremities, and that either tab may be hooked over the other at the rear of the tie. Other modifications of the invention will occur to those skilled in the art.

40 Having thus described my invention, what I claim is:

1. The combination with a necktie having its side edges overlapping at the rear of the necktie, and having a label secured at its ends transversely across the two overlapping side edges of the necktie, of a flexible fold-over band wrapped around the necktie,

45 said band having a front panel disposed in front of the necktie, and two tabs projecting laterally from opposite ends, respectively, of said front panel and folded in overlapping relation over the rear of the necktie, said tabs having interlocking portions to secure said band releasably around the necktie, said front panel being of a size to bear indicia on its front identifying the necktie, and said label also bearing some identifying indicia on its rear face,

50 one of said tabs having an integral tongue projecting downwardly from the lower edge thereof and engaging under said label intermediate the ends of said label, thereby to hold the band from slipping down on the necktie.

55 2. The combination with a necktie having its side edges folded over the front of the necktie at the rear thereof, and having a label secured at its ends transversely across

the two folded side edges of the necktie, of a flexible foldover band wrapped around the necktie, said band having a front panel disposed in front of the necktie, and two tabs projecting laterally from opposite ends, respectively, of said front panel and folded over the folded side edges of the necktie at the rear thereof, said front panel being of a size to bear indicia on its front identifying the necktie, and said label also bearing some identifying indicia on its rear face, one of said tabs, at least, having an integral tongue projecting downwardly from its lower edge and engaging under said label intermediate the ends of said label, thereby to hold the band from slipping down on the necktie.
